ELECTROMAGNET FOR RAIL FISSURE
DETECTORS

Chester W. McKee and Richard W. McKee, Chicago, Ill., assignors, by mesne assignments, to Teledetector, Inc., a corporation of Delaware

Application May 20, 1947, Serial No. 749,166

15 Claims. (Cl. 175—183)

1

This invention relates to an electromagnet for a rail fissure detector and is a continuation in part of applicants' co-pending application, Serial Number 628,146, filed November 13, 1945. This co-pending application disclosed a three-pole magnet while the present application discloses two three-pole magnets and a five-pole magnet. All claims to magnets as such will be presented in this case.

The general object of all rail fissure detecting apparatus is to distinguish fissures from harmless flaws such as burns during the performance of the exploratory step. One method of distinguishing was disclosed in the Frickey and McKee Patent No. 2,388,683, wherein an aircore pickup coil having a length along the rail of less than the length of the residual flux field above that portion of a rail ball containing a transverse fissure, will give for a burn a signal of longer time duration than that for a fissure. As a matter of practice, this method of distinguishing burns from fissures during the exploratory step requires a concentration of attention on the screen of the recording cathode ray tube that tires an operator. Moreover, the tube persistency is limited to under four seconds and the operator is never certain as to his conclusion.

With the development of the testing of a trailing, sustained field by the present applicants as disclosed in the above mentioned co-pending application, also employing the small aircore coil, applicants noted that the harmless flaws gave such weak potential signals in the pickup that they could be distinguished from fissure signals by means of intensity alone. In short, by means of a suppressor, the signals from a burn spot could be eliminated in the amplifier so that they would not actuate a pen writing unit.

The general object of this invention is to increase the flux in the trailing sustained field over the amount produced by the three-pole magnet first disclosed in the co-pending application. The reason for doing this is not to provide a stronger field in which the flux responsive means will function, for applicants' high gain amplifier is able to intensify signals now received to a point far greater than is usable. The reason for increasing the flux resides in the fact that the more it is increased, the greater the difference between a potential signal from a harmless flaw, such as a burn, and a potential signal from a fissure.

Applicants are prepared to offer an explanation for this at this time, although they were not prepared to do so at the time of filing the co-pending application. Referring to Figure 1, the

5 numeral 10 generally identifies a rail having a ball 12, a web 14, and a base 16, and the numeral 18 identifies a vertically disposed electro-magnet having north and south poles. This magnet has moved from the point 20 to the position shown in a selected period of time. Around this magnet are indicated lines of force 22, creating what applicants refer to as a trailing sustained field 24 and a leading sustained field 26. The numerals 28 and 30 identify two internal fissures 10 in the rail ball which are assumed to be of identical size, and the numerals 32 and 34 identify two like sized burns having identical hardened shells in the rail ball. The arrow 36 is at the 15 point distant from the magnet 18 where a magnetometer of the type described in the copending application (Experiment 2 on pages 7-11 thereof) ceases to show any difference between the strength of the field around the rail ball due 20 to energization of the magnet 18. That part of the rail to the left of the point 36 may be considered as residually magnetized, and that part to the right as being in the sustained field 24.

Applicants have indicated by dotted lines in the 25 fields 38 and 40 their concept of the direction of flux flow in residual fields around those portions of a rail containing a fissure and a burn spot respectively. In both residual fields, the concept is that the flux is parallel to the length of the 30 rail and when these fields are traversed by either the short air core coil of the applicants or the multiple iron core pickups of the A. A. R., a non-discriminatory signal will be produced if the potential signals are functioning a pen unit. If 35 applicants' air core coil is hooked to an amplifier connected to the plates of a cathode ray tube, the differences in time duration of signals from a fissure and a burn will be observable, and there will also be differences in intensity. However, 40 the intensity of a potential signal produced by a residual flux field modified by a small fissure, i. e. twenty per cent, is approximately the same as the intensity from a residual flux field around many burns, and it follows that one cannot adjust the amplifier to suppress signals of this 45 intensity without suppressing potential signals from small fissures.

In testing the trailing sustained field, the situation appears to be different. Figure 2 is an enlargement of the right end of Figure 1 showing the rail ball 12, the magnet 18 and the trailing flux field 24. Under recognized theories of flux lines in air around a bar magnet, the dot-dash lines numbering only two, namely 42 and 44, for 55 illustrative purposes indicate the position of the

flux in the trailing field 24, assuming that the rail 12 is not in the field. Assume now that these lines of force such as 42 and 44 are intersected by a line 46 which is coincident with the crown of a rail ball when the latter is placed in proper position with respect to the magnet 18. It is not necessary to demonstrate the fact that the angle a is equal to the angle b , and that a flux responsive means moved along the line 46 at a constant rate of speed (and at a constant distance from the magnet 18) will develop no voltage.

When a rail 12 is placed in the position shown in Figure 2, this statement will for all practical purposes continue to be true. The rail being much more permeable than air will cause the flux to flow along lines, such as 48, 50 and 52, and this will have the effect of producing angles such as C and D with the crown of the rail, which is parallel to the movement of the pick-up. The absence of a more permeable path adjacent the north pole of the magnet 18 will tend to permit the lines of flux to follow the path which they assume when the magnet is completely surrounded by air. It may be that the angles C and D are not quite equal, that as a matter of fact, the angle becomes greater, the greater the distance from the magnet 18. However, the difference will not be great, and most importantly, applicants' pickup coil is short as indicated by the two sides 54 and 56 of a coil generally identified by the numeral 58. For all practical purposes, therefore, the coil is traversing a field in which the angle between the lines of force and its direction of movement is constant when the rail possesses perfect contour and a perfect cross section.

Figure 3 is an enlargement of the area defined by the rectangle 60 in Figure 2, 30 being the fissure in the rail ball 12, and 34 being the burn. The lines of force 48 to 52, as well as many other lines of force are indicated. When the lines of force through the burn 34 pass from the rail ball into the air, their direction is not changed. This follows from the concept of magnetism that there is no angle of refraction when flux passes from a material having one density (permeability) into a material having another density, as in the case of light passing from air into glass. It is true that the burn will slightly change the angle of the flux due to its providing a shorter path or due to the alteration of the grain structure of the steel at the surface, as by hardening, but the center of the flux circuit, i. e., its motivating force, is the magnet 18. In the magnet circuit, the effect of the burn is negligible because the lines of force are governed by their relationship to the field as a whole which tends to resist modification by the burn. This should be contrasted with the effect of the burn spot on a residual magnetic field where the steel around the burn substitutes itself for the magnet 18 as the main element of the flux circuit. In the latter case, the burn, being on the surface of the rail ball, immediately adjacent to the path of the flux responsive means, has an advantage over the internal fissure in creating a flux field showing changes of direction and intensity which will produce a voltage in the pick-up circuit. Referring now to the effect of an internal transverse fissure on the flux field 24, and again referring to Figure 3, the fissure 30 is a comparatively small fissure. It extends perhaps one-third of the height of the rail ball and if it extends one-half the width of the rail ball, it will occupy one-sixth of the cross sectional

area of the rail ball, or but slightly more than a 15% fissure. This fissure will substantially change both the angle of the flux in the field 24 immediately adjacent to the top of the rail ball and will change the concentration of flux per unit area. The fissure 30 is a separation of the metal inside the rail ball so as to create two faces, 62 and 64, which are very close together, but which, when the rail is magnetized, undoubtedly produce opposite polarity in the faces 62 and 64. What is more important, across the fissure, the path for flux is a vacuum or air and is much less permeable to the flux than is the rail ball itself. The result is that lines of force, such as 66 and 68, will tend to follow the paths, such as 70 and 72 and in the adjustment, these lines of flux will be squeezed into a smaller area indicated by the square 74. Moreover and importantly, this area 74 will be followed by an area 76 having a reduced number of lines of flux because of the comparatively dead space, dead from the standpoint of flux density, 78, immediately behind the fissure 30. When a pick-up such as 58 successively passes through these zones 76 and 74, it will reflect two voltage producing factors, the abrupt changes in flux angularity with respect to its course, and the changes in the flux density.

From the foregoing it seems that the greater the volume of flux having a single polarity that can be pushed out from the pole of the trailing magnet, and the closer that the flux responsive means can be mounted to that magnet, the more marked will be the difference between a potential signal created by an internal defect in the rail ball and the potential signal created by a surface defect such as burns, shells or flow.

The general object of this invention is, therefore, to increase the intensity of the trailing sustained field 24.

The specific object of this invention is to attain the general object without increasing the E. M. F. required to operate a magnet. From a study of ordinary college textbooks on magnetization, one would conclude that this cannot be done. In such discussions, the time element is completely ignored. Thus, in Lord Kenyon's careful establishment of the accepted hysteresis curve, the values are obtained for any given magnetizing force by applying the magnetizing force until no further change in the flux field in the metal is perceived. Presumably, if a given rail can be saturated with a magnetizing force represented by "X" in four seconds, a magnetizing force of 2X might require only three seconds. It would seem that the time required would vary inversely and probably proportionately with the magnetic force applied. At any event, the experiments of applicant, Chester W. McKee, and his associate, Royal Frickey, showed many years ago that the strength of the residual magnetic field varied indirectly with the rate of speed at which a magnet moved along the top of the rail. These same observations have been made in studying the strength of the trailing sustained field, and applicant herein provides a magnet which has five poles instead of three for the purpose of lengthening the time in which the magnetic force is applied to the rail, even though for all practical purposes only the field created by the trailing magnetic pole is being tested.

A feature of the invention is the fixed relationship of the magnet pole pieces or shoes to each other and their close proximity to each other which is believed to give an uninterrupted

swinging motion to the molecules which assists the trailing pole piece in giving them a final set in the trailing sustained field.

The invention is disclosed in three embodiments in four sheets of drawing. The first embodiment is shown in Figs. 4 and 5 which are reproductions of Figs. 9 and 10 of co-pending application Serial No. 628,146. The second embodiment is disclosed in Figs. 6, 7 and 8 which show a five-pole magnet in side elevation, plan view and end elevation respectively. Fig. 9 is a view of the magnet case. The third embodiment, which is the preferred form, is disclosed in Figs. 10, 11 and 12, being a side elevation, a bottom view and an end view respectively.

The first embodiment

The description of the first embodiment of the invention will be taken directly from the co-pending application as follows:

Referring now to Figures 4 and 5, 344 and 346 are a pair of aluminum bars maintained in spaced relationship by means of four sets of independently rotatable, roller bearing wheels such as 348 and 350, with necessary shafts and locking means. Vertically disposed between said bars 344 and 346 and between two sets of rollers at each end are iron cores 352 and 354. Mounted on the lower end of each is a wedged shaped member 356 and 358 which is of conductive metal, and which has an elongated horizontal flux transmitting face such as 361 or 363.

The upper ends are joined together by a top bar of iron 360 so that in substance the magnet appears to be an ordinary inverted U-shaped magnet. The two cores 352 and 354 are spaced apart by approximately eleven inches.

Disposed intermediate to core members 352 and 354 is a similar core member 362 of the same cross dimension and same material, excepting that this member has its upper end 364 mounted on a two-inch brass, right parallelogram 366 so that there will be no direct flow of flux through metal from the top bar 360 to the middle core member 362. Attention is also called to the fact that the lower end 368 is spaced from the ball 370 of the rail by a much greater distance than are the pole pieces on the two outside core members 352 and 354. In fact, the spacing of the central core member 362 is approximately three-eighths of an inch while the spacing on the end members is one-sixteenth of an inch. This will be commented upon shortly.

The three core members 352, 362 and 354 are wound in series with identical windings on the outside core members 352 and 354 and an opposed winding on the central core member 362. Expressed differently, the central core member 362 is wound in series opposition to the two outside core members. The coils are wound for 115 volts D. C. with a power consumption of approximately 400 watts. The leads are indicated by the conductors 134 and 138 which bear the same numbers on the wiring diagram, Figure 4.

The spacing of the upper member of the intermediate core member 362 from the top bar 360 and the spacing of its lower end 368 from the rail ball are a result of experiment. The experiments were performed with the magnetometer while the magnet was both stationary and moving and it was found that the spacing described gave the best results. It is appreciated that many factors enter into the relationship of the parts of this magnet. Prominent among these is the magnet's capacity and the capacity of the

generator, the size of the rail ball that is being tested, and the particular materials used in the magnet and the magnet frame. It is thought however, that the greater spacing of the intermediate core member from the rail ball than the spacing of the two outside core members is important and that the spacing of the upper end of the intermediate core member 362 from the top bar 360 by a non-conductor is important. The reduced conductivity for flux of the core member 362 may have a tendency to force flux on both sides of the magnet so that there is an increased flow of flux from the lateral sustained fields through the air to the bar 360 in the central position of which above the core 364 there must be a great complexity of molecular polarity.

As actually built, the poles 356 and 358 are north poles and the pole 368 is a south pole, and the leads off the flux responsive pick-up are connected accordingly. It is not material, however, that these poles have this named polarity, for the apparatus would work equally well, it is at present believed, if the two outer poles, 356 and 358, were south poles and the intermediate pole 368 was a north pole, the leads from the pick-up 168 would of course have to be reversed.

This magnet gives the lateral sustained field on either side of the outside pole pieces 356 and 358 mentioned in Experiment 2 in the introductory part of the disclosure. Assuming that the magnet is moved to the right, applicants refer to the sustained field which follows the pole 356 for a distance measurable by the magnetometer up to about six feet as the trailing sustained field. Applicants are confident although experiment has not yet been made, that, assuming the same directional movement of the magnet, the pick-up could be mounted in advance of the pole 358 and would find there a sustained field. This is called the leading sustained field. It is not thought that testing in the leading sustained field would be as effective as testing in the residual or trailing sustained field, for the reason that there would not have been the beneficial oscillation of the molecules to negative pre-testing magnetic fields around the rails that there has been when the testing is done in the trailing sustained field."

The second embodiment

The second embodiment of the invention is shown in Figures 6, 7 and 8. Referring to Figure 6, 90, 92, 94, 96 and 98 are spaced highly permeable bars of iron held in parallel spaced relationship by means of a non-magnetic head piece 100 and a pair of aligned base members 102 and 104. Head member 100 is held to each bar, such as 90, by a bolt 106 threadedly seated in a tapped hole 108 in the upper end of the bar. The bar 90 is round. A pair of collars, 110 and 112, are mounted on each bar for confining the windings 114 in the position indicated. The parallel supports 102 and 104 are mounted on two types of shoes which in turn are mounted on the bottom of the bars 90 to 98.

The first type of shoes may be called the critical pole shoes, such as 116, 118 and 120, and the second type of shoes may be called the non-critical pole shoes, such as 122 and 124. The critical shoe is that shoe which establishes the polarity in that portion of the rail in which the flux responsive means functions. It follows that where the flux responsive means is positioned in either the trailing or the leading field, the outside poles of a multiple pole magnet will be the critical poles.

Examining now critical pole shoe 116, it is seen to consist of a casting made of high flux permeable material having a downwardly directed wedge-shaped configuration with rounded apex 122. See also Figure 7. This shoe is tapped to form a circular opening 124 in which fits the magnet 90. The two are joined by any suitable means. The shoe 116, referring to Figure 8, has a width approximating that of the pole of a standard rail 123, namely 3", and as may be seen in Figure 8, the base members 102 and 104 are fastened to the shoes 116, 118 and 120 by a means of bolts, such as 126, which hold the base members 102 and 104 directly to the sides of the shoes.

The non-critical shoes, such as 122 and 124, referring to Figure 6, consist of a segment of a cylinder which is spot faced to form a cylindrical seat 128 in which is mounted the lower end of the magnet 92. They are held in assembled similar relationship by a bolt 130. Each side of the shoe is tapped, as at 132, see Figure 7, to receive a bolt through the adjacent base member 102.

Three sets of wheels support the magnet referring to Figures 6 and 8. Each set of wheels comprises four wheels such as 134, 136 and 138 which are mounted by some standard bearing assembly on shafts, such as 140 and 142. These shafts 140 and 142 are mounted in fixed axial position in the base members 102 and 104.

The windings on the magnets are all identical, but the windings on magnets 92 and 96 are reversed with respect to the windings on 90, 94 and 98 so that if the windings produce a south pole at the lower end of the magnet 98, 96 will have a north in the same position, 94 a south, 92 a north and 90 a south.

The thought governing the provision of different types of pole pieces such as 116 and 122 is this. The critical pole shoe will concentrate flux in the rail beneath the shoe and tend to give the molecules in the rail a more definite set that the non-critical shoe which disperses the flux over a much larger area. The purpose of having reversed poles in alignment is to cause at least a swinging movement of the poles of the molecules in the rail and then the final pole, in this case, 116, assuming the magnet is moving to the right, will be able to give a more definite set to the molecule poles than is possible if the magnet 116 alone were working upon the molecules. Applicants do not believe that accepted hysteresis curves will be useful in understanding the functioning of this magnet. According to Lord Kenyon's hysteresis curve, the amount of residual magnetism in the rail after the pole 120 has passed over it will be exactly the same as the amount in the rail after the pole 118 has passed over it. As mentioned heretofore, this is based on conclusions reached regardless of time. Applicants believe that where the first magnet such as 98 only partially saturates the rail, the reversal by magnet 96 and then the remagnetization by magnet 94 will raise the flux density to a point higher than was raised by the magnet 98. On the reversal of the magnetization when the magnet 92 passes over the rail, the reverse polarization will not be as great, and finally the wedge shaped head 116 of magnet 90 will give a stronger magnetization to the molecules than either magnet 98 or 94 could do.

The advantage of having the wheels mounted rigidly in the frame lies in the fact that they will carry the magnet over low spots in the rails better than would spring-mounted trucks. On

the average, accurate spacing between the poles of the magnet and the top of the rail is better obtained by wheels mounted in this fashion.

The configuration of the cross section of the wedge head 116, referring to Figure 6, is parabolic about a center 127 and is believed to provide the best path for flux flowing from a magnet such as 90 into a rail ball having a somewhat rectangular cross section.

In Figure 9, which is a reproduction of a portion of Figure 5 of the said co-pending application, the numeral 146 identifies a casing which is mounted by end bolts 148 and 150 in seats, referring to Figure 6, 152 and 154, on the opposite ends of the member 100.

The third and preferred embodiment

The third and preferred embodiment of the magnet is illustrated in Figures 10, 11 and 12.

20 This is a three-pole magnet having, however, five energized cores. Referring to Figure 10, the five cores 160, 162, 164, 166 and 168 are suspended from a non-magnetic header 170. The windings on cores 160, 162, 166 and 168 are in the same 25 direction, so that their bottom poles will have a like polarity, in this case north. The core 164 is wound in an opposed direction so that its bottom pole is of an opposite polarity, in this case south. To the bottom of the poles 160 and 162 is fastened 30 a block shoe 172, which referring to Figure 12, has a width substantially approximating that of a rail ball 174 and extends downwardly to a point just above the rail ball. A similar block shoe 176 is attached to the bottoms of the cores 166 35 and 168. To the bottom of core 164 is fastened a shoe 178 which is a segment of a cylinder and is spaced from the rail ball by a distance greater than the block shoes 172 and 176 and the rail ball. The shoes are held in fixed, assembled 40 relationship by rails 180 and 182 and are suspended above the rails by pairs of wheels such as 184.

The whole bottom surface of the block shoes such as 172 is of north polarity and testing seems 45 to indicate that this shoe pushes a greater amount of flux into the trailing sustained shoe than does either of the other two embodiments of this invention. It is believed that the improved result stems in part from the greater polarization of 50 the trailing shoe or pole piece 172 as compared with shoe 178, in the example shown, shoe 172 having twice the polarization of shoe 178. The problem is to get the best possible, directional magnetism in the rail ball following the trailing 55 shoe 172 and this depends upon the shape of the shoe 172, its proximity to the ball tread, its degree of polarization, and the effect of the preceding magnetized shoes on any directional set in the molecules in the rail before any magnetization.

The advantages of these multiple-pole magnets reside in the constant relative spacings of the poles above the rail and the spacing of the holes from each other, which is accomplished by the 60 magnets being rigidly fixed on the frame.

Applicants' magnet is not a mere aggregation of magnets. When any one of three magnets disclosed in this application moves over a rail, applicants' concept is that the molecules are placed in motion which motion is not completely stopped until the last magnet has passed over a given portion above the rail ball. This is to be contrasted with earlier magnets used by others including the applicants' wherein a single magnet having a north pole adjacent the rail is positioned ahead of the

power car, a second magnet having its lower pole of south polarity is positioned at the rear of the power car, and a third magnet is positioned on the fissure detector car itself, this last magnet having its north pole directed downwardly. This last-mentioned magnet arrangement does not accomplish the result obtained by the single magnet having a plurality of poles disclosed herein. Applicants' magnets function because they are mounted on a single frame which maintains their bottom pole pieces at the proper relative distances from the rail ball at all times.

In the claims, the pole pieces and magnets are referred to as even numbered and odd numbered. In Figure 4, pole pieces 356 and 358 are odd numbered and 368 even numbered; in Figure 6, pole pieces 116, 118 and 120 are odd numbered and 122 and 124 are even numbered; and in Figure 10, 172 and 176 are odd numbered and 178 even numbered.

Having thus disclosed our invention, what we claim is:

1. A rail magnet for progressively creating a trailing sustained field in the balls of rails lying in track comprising a frame having a base, means on the frame for movably supporting it at a constant distance above and adjacent to the treads of the rail balls, and a plurality of magnetizable elongated cores mounted in fixed position with one pole of each mounted in a general straight alignment along the frame base, each pole having a polarity opposite to the polarity of an adjacent pole and being closer to said adjacent pole than to the opposite pole of its own core.

2. A rail magnet for progressively creating a trailing sustained field in the balls of rails lying in track comprising a frame having a base, means on the frame for movably supporting it at a constant distance above and adjacent to the treads of the rail balls, and a plurality of magnetizable elongated cores mounted on the frame and each having a downwardly directed pole along the frame base, the centers of said poles being equally spaced from each other and in substantial alignment and adjacent poles being closer to each other than to the opposite pole on their own core, the pole pieces on the odd numbered magnets having one polarity and the pole pieces on the even numbered magnets having an opposite polarity.

3. The rail magnet of claim 1 wherein the odd numbered pole pieces are substantially closer to a plane containing the outer surfaces of the supporting means than are the even numbered pole pieces.

4. The rail magnet of claim 1 wherein the pole piece at one end of the line of pole pieces is considered the trailing pole piece and wherein that pole piece is positioned close to a plane containing the outer surfaces of the supporting means and wherein the next adjacent pole piece is positioned at a substantially greater distance inwardly of said plane.

5. A rail magnet for progressively creating a trailing sustained field in balls of rails lying in track comprising a pair of elongated members spaced by approximately the width of a rail ball, supporting wheels therebetween adapted to ride the ball tread, a plurality of aligned, vertical, magnetizable elongated cores fixedly supported between said members and having their centers equally spaced from each other, the space between adjacent centers being substantially less than the length of the cores, means for giving one polarity to the odd numbered pole pieces, and

means for giving an opposite polarity to the even numbered pole pieces.

6. A rail magnet for progressively energizing the balls of rails lying in track comprising a frame having a base, means on the frame for movably supporting it above and adjacent to the treads of the rail balls, three electromagnets having straight cores vertically and fixedly positioned on said frame with their lower ends near the frame base so as to be adjacent the tread of the rail ball, said cores being substantially closer together than their lengths, the end cores having a like polarity at their bases and the middle core having an opposite polarity to its base, and a pole piece on the bottom of one end magnet, said pole piece having a uniform, downwardly directed blunted, wedge-shaped cross section with the blunt edge transverse to a line connecting the pole pieces.

7. The magnet of claim 6 wherein the pole piece on the middle magnet is spaced inwardly of a plane containing the outer surface of the supporting means by a distance substantially greater than the distance between the pole piece on the end pole and the same plane.

8. The magnet of claim 6 wherein a magnetic conductor joins the upper ends of the two end cores to each other.

9. A rail magnet for progressively energizing the balls of rails lying in track comprising a frame having a base, means on the frame for movably supporting it above and adjacent to the treads of the rail balls, five electromagnets having straight cores vertically and fixedly positioned on said frame with their lower ends near the frame base so as to be adjacent the tread of the rail ball, the lower ends being substantially closer to each other than the length of a core, the odd numbered cores having a like polarity at their bases and the even numbered cores having an opposite polarity at their bases, and a pole piece on the bottom of one end core, said pole piece having a uniform, downwardly-directed parabolic, cross section with the apex transverse to a line connecting the pole pieces.

10. A rail magnet for progressively energizing the balls of rails lying in track comprising a frame having a base, means on the frame for movably supporting it above and adjacent to the treads of the rail balls, five electromagnets having straight cores vertically and fixedly positioned on said frame with their lower ends near the frame base so as to be adjacent the tread of the rail ball, the lower ends being substantially closer to each other than the length of a core, the odd numbered cores having a like polarity at their bases and the even numbered cores having an opposite polarity at their bases, a pole piece on the bottom of one end core, said pole piece having a uniform, downwardly-directed parabolic, cross section with the apex transverse to a line connecting the pole pieces, and a pole piece on the bottom of the next adjacent core, said latter pole piece having a downwardly directed, convex cylindrical surface with its axis at right angles to a line connecting the pole pieces.

11. A rail magnet progressively energizing balls of rails lying in the track comprising a pair of elongated members spaced by approximately the width of a rail ball, supporting wheels therebetween adapted to ride the ball tread, five aligned, vertically disposed, magnetic cores having their lower ends mounted fixedly between said members, said lower ends being substantially closer to each other than the length of a core, the odd numbered cores having one polarity at their lower

ends, the even numbered cores having an opposite polarity at their lower ends, and a non-magnetic bar parallel to the elongated members and fastened to the top of each core.

12. A rail magnet for progressively creating a trailing sustained field in the balls of rails lying in track comprising a frame, means on the frame for movably supporting it at a constant distance above and adjacent to the tread of a rail ball, a plurality of magnetizable elongated cores mounted on said frame, and each having a pole lying along a generally straight line for positioning next to the rail, said poles being substantially closer to each adjacent other pole than to its opposite pole on its own core.

13. A magnet for creating a lateral field at one side thereof in a magnetizable object having a flat surface comprising a frame, means mounted on the frame and engageable with the flat magnetizable object for spacing the frame from said object, a plurality of magnetizable elongated cores mounted on said frame and spaced from each other by a distance substantially less than the length of the cores, adjacent cores having both poles of opposite polarity, and the poles of one polarity having a selected surface area and lying in a plane which will be at a selected distance from the plane of the surfaces of the spacing means and the poles of the other polarity being of a substantially different surface area and being at a greater distance from said plane.

14. A rail magnet for progressively energizing the balls of rails lying in track comprising a frame having a base, means on the frame for movably supporting it above and adjacent to the tread of a rail ball, two aligned vertically disposed magnetic cores mounted in fixed position along the

frame base, electromagnetic windings on each core for giving both core bottoms a like polarization, a magnetically conductive shoe mounted across the bottoms of both cores, and a similar vertically disposed magnetic core mounted in alignment with the first two on said frame, and electromagnetic windings for giving the bottom of this core a polarization opposite to that of said shoe.

15. The rail magnet of claim 14 wherein the elongated shoe is positioned closer to the plane containing the outer surfaces of the supporting means than is the third pole piece.
